DESIGN FOR A BREAD KNIFE OR SIMILAR ARTICLE

Lon J. Oliver, Chillicothe, Ohio

Application March 5, 1943, Serial No. 109,671

Term of patent 14 years

To all whom it may concern:

Be it known that I, Lon J. Oliver, a citizen of the United States, residing at Chillicothe, in the county of Ross and State of Ohio, have invented a new, original, and ornamental Design for a Bread Knife or Similar Article, of which the following is a specification, reference being had to the accompanying drawing, forming a part thereof.

Fig. 1 is a perspective view of a bread knife or similar article showing my new design;

Fig. 2 is a transverse sectional view taken therethrough on the line 2—2 of Fig. 1.

I claim:

The ornamental design for a bread knife or similar article, as shown.

LON J. OLIVER.
